BEER TAP

Robert O. Kirchhan, Milwaukee, Wis., assignor to Milwaukee Brass Specialty Company, Milwaukee, Wis., a co-partnership composed of Charles O. Kirchhan and Robert O. Kirchhan

Application May 28, 1934, Serial No. 727,844

3 Claims. (Cl. 285—40)

This invention relates to new and useful improvements in beer taps and has as its primary object to provide a more conveniently applied and better constructed tap.

5 Another object of this invention is to provide a tap so designed that the means for clamping the sealing gaskets are located a substantial distance from the head of the keg to be readily accessible.

10 Another object of this invention is to provide a tap wherein right and left handed threads are utilized to afford a rapid clamping action.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated two complete examples of the physical embodiment of my invention constructed according to the best modes I have so far devised for the practical application of the principles thereof, and in which:

Figure 1 is a view partly in longitudinal section and partly in side elevation of a beer tap embodying this invention;

Figure 2 is a bottom view of the tap;

Figure 3 is a detail side view of the lower portion of the tap;

Figure 4 is a view similar to Figure 1, but illustrating a slightly modified embodiment of this invention;

Figure 5 is a view partly in section and partly in side elevation illustrating another modification of this invention; and

40 Figure 6 is a cross section view taken through Figure 5 on the plane of the line 6—6.

Referring now more particularly to the accompanying drawings in which like numerals indicate like parts throughout the several views, the 45 numeral 5 designates the head of a conventional keg having a metal bung 6 secured therein. The bung is of conventional construction and is provided with a shouldered flange 7 encircling its bore 8. The tap, which is indicated generally by 50 the numeral 9, is attached to the bung by engaging lugs 10 under the shoulders of the flange 7. The lugs 10 are carried by and project inwardly from the lower end of a sleeve 11, which is internally threaded to receive a clamping nut 12. The clamping nut 12 is loosely journalled

on the main body 13 of the tap and is confined against axial shifting between a shoulder 14 integral with the tap body and a collar 15 threaded on the lower end portion 16 of the body.

The collar 15 is run onto the threaded portion 5 16 until its upper end abuts a shoulder 17 and is held against retrograde movement by two screws 18 threaded in the collar with their inner ends engaging the lower portion 16 of the body and their heads received in elongated slots 19 in 10 the internally threaded sleeve 11.

The sleeve 11 is thus held against relative rotation with respect to the body of the tap so that upon rotation of the nut 12, the entire body will be drawn downwardly with respect to the sleeve. 15 Hence, if the sleeve is engaged with the bung as shown in Figure 1, the rubber gasket 20 confined between the shouldered head of the bung and the lower face of the collar 15 and the body of the tap, will be tightly clamped to afford a fluid-tight joint as will be readily apparent.

The body of the tap is longitudinally bored to loosely receive a discharge pipe 21, which as is customary, extends down to the bottom of the keg and affords the means for withdrawing the contents therefrom. To force the contents of the keg out through the discharge pipe, fluid under pressure is injected into the keg through a valved opening 22, which may be of any conventional construction.

The upper end of the body is enlarged to afford a seat 23 for a rubber sealing gasket or washer 24, which is clamped down onto the seat 23 by a sleeve 25 drawn downwardly by a clamping nut 26.

The clamping nut 26, and the nut 12, have large wings to facilitate the application of turning force thereto, and inasmuch as both nuts are located at a substantial distance above the head of the keg, it is apparent that the application of the tap is materially facilitated.

It is also evident that the tap need not be disassembled to apply the same.

The application of the tap to the bung may be further facilitated and rendered more rapid by 45 the use of right and left threads whose conjoint action is accumulative to increase the rapidity with which the tap may be tightened down onto the bung.

A construction employing such right and left threads is illustrated in Figure 4. The tap shown in this modification in its general aspects is the same as that illustrated in Figure 1, but the arrangement of the clamping means for securing it to the bung is different.

As in the embodiment described, an internally threaded sleeve 11' is provided and a collar 15' is threaded on the lower portion 16' of the tap body, the collar 15' being retained against loosening by screws 18' whose heads, like in the embodiment shown in Figure 1, are slidably received in elongated slots 19' in the sleeve 11'.

The clamping nut 21, however, is not merely loosely journaled on the tap, but has a threaded connection 28 therewith. This threaded connection 28, between the clamping nut 21 and the body of the tap, is left handed. The nut 21 also has a right hand threaded connection 29 with the sleeve 11'. Consequently, upon right handed rotation of the nut 21 the nut will be drawn into the sleeve 11' as in the embodiment shown in Figure 1, and simultaneously therewith, the tap body will be drawn downwardly into the nut so that the clamping action necessary to attach the tap to the bung is very rapid.

Another modification of this invention is illustrated in Figures 5 and 6. In this embodiment the general construction is similar to that illustrated in Figures 1 and 2, but the means for securing the sleeve against relative rotation with respect to the body of the tap and the specific construction of the arms on the clamping nut is different.

The collar 30, threaded on the lower end of the tap body, is secured against retrograde rotation by a set screw 31 and at diametrically opposite sides, this collar has rectangular lugs 32 projecting radially therefrom for sliding engagement in longitudinal grooves 33 opening to the bore of the sleeve 34.

As in the embodiment hereinbefore described, the sleeve 34 is threaded for engagement with the clamping nut 35, and as will be readily apparent, the sleeve is held against rotation with respect to the body by the engagement of the lugs 32 in the grooves 33, so that rotation of the clamping nut draws the body down into the sleeve.

Attention is particularly directed to the specific construction of the arms 36 on the clamping nut. To insure maximum strength, these arms are cast tubular and preferably have a cylindrical cross section. The provision of three arms in the place of two and the upward angular disposition of the arms further facilitates the application of the tap.

In other respects, the embodiment illustrated in Figures 5 and 6, is the same as that shown in Figures 1 and 2.

From the foregoing description taken in connection with the accompanying drawings, it will be readily apparent to those skilled in the art, that this invention affords a novel and very practical construction for beer taps and that the heretofore objectionable feature of having one of the clamping nuts located directly adjacent the head of the keg is entirely obviated, thus materially facilitating the application of the tap.

What I claim as my invention is:

1. A beer tap for attachment to the bung of a beer container, comprising a tubular body, a sealing gasket adapted to be clamped between the bottom of the tubular body and the bung, an externally threaded hollow screw freely rotatably mounted on the lower end portion of the body,

the bore in the hollow screw being large enough to allow its engagement and disengagement over the lower end of the body, a separate collar secured on the lower end of the body beneath the hollow screw with its lower face providing a large surface area engaging the gasket and its upper face providing a shoulder to limit relative axial motion between the hollow screw and the tap body in one direction, a sleeve internally threaded at its upper end for threaded engagement with the hollow screw, said sleeve being fitted over the lower end of the body and the hollow screw, means on the sleeve to effect an interlocking connection with the bung, and means carried by the collar and engaging the sleeve to hold the same against relative rotation with respect to the tap body so that rotation of the hollow screw effects relative axial movement between the tap body and the sleeve to clamp the gasket between the tap body and the bung and secure the interlocking connection between the sleeve and the bung.

2. A beer tap for attachment to the bung of a beer container comprising, a tubular body having a shoulder, a clamping nut loosely journaled on the body and arranged to abut the shoulder, a collar threaded on the body to coact with the shoulder and restrict relative axial movement between the clamping nut and the body, a sleeve encircling the body and the collar thereon, said sleeve having means to effect an interlocking connection with the bung and having a threaded connection with the clamping nut, and a screw passed through an elongated slot in the sleeve and threaded in the collar with its inner end bearing against the tap body to simultaneously lock the collar on the tap body and secure the sleeve against relative rotation with respect to the tap body while permitting a degree of relative motion between the sleeve and the tap body, whereby rotation of the clamping nut draws the tap body into the sleeve against the bung when the sleeve is engaged with the bung.

3. A beer tap comprising a body member having an annular shoulder facing its lower end, a collar detachably secured on the lower end of the body member at a distance from said shoulder and having a transverse surface providing a second shoulder near the lower end of the body member, an internally threaded sleeve encircling the collar and the adjacent lower end portion of the body member, said sleeve having means to connect the same to a bung fitting, means on the collar slidably received in a longitudinal groove opening to the bore of the sleeve to hold the sleeve against relative rotation with respect to the body member, and an externally threaded hollow one-piece clamping screw freely rotatably mounted on the body member with a portion thereof confined between said two shoulders so as to be held thereby against axial displacement from the body member, the bore of said screw being large enough to allow engagement and disengagement of the screw over the lower end of the body member when the collar is removed, and the external threads on the screw engaging the internal threads of the sleeve so that rotation of the clamping screw effects relative longitudinal motion between the body member and the sleeve.

ROBERT O. KIRCHHAN.
